US00D609878S

(12) **United States Design Patent**
Tham et al.

(10) **Patent No.:** **US D609,878 S**
(45) **Date of Patent:** **** Feb. 16, 2010**

(54) **CURVED CRACKER**

(75) Inventors: **Kenchu A. Tham**, Sparta, NJ (US);
Edward Kevin McHugh, Oakland, NJ (US); **Steven Peter Zubanas**, Verona, NJ (US); **Zena A. Forte**, Blairstown, NJ (US); **Randy Blandine**, Ringwood, NJ (US)

(73) Assignee: **Kraft Foods Holdings, Inc.**, Northfield, IL (US)

(**) Term: **14 Years**

(21) Appl. No.: **29/304,152**

(22) Filed: **Feb. 26, 2008**

(51) **LOC (9) Cl.** **01-01**

(52) **U.S. Cl.** **D1/128**

(58) **Field of Classification Search** D1/100-199; D28/8.2; D24/102; 426/89, 94-95, 100-104, 426/293, 302, 305-307, 383, 438-439, 512, 426/516-518, 808, 138, 144, 543, 549-550, 426/496; D21/484-505; D20/22, 23, 27, D20/28; D32/40; D6/601
